UNITED STATES PATENT OFFICE.

DAVID E. FOLLEY, OF MEDFORD, MASSACHUSETTS.

PUZZLE.

1,102,576.

Specification of Letters Patent.

Patented July 7, 1914.

Application filed March 23, 1914. Serial No. 826,481.

To all whom it may concern:

Be it known that I, DAVID E. FOLLEY, a citizen of the United States, and resident of Medford, county of Middlesex, State of Massachusetts, have invented an Improvement in Puzzles, of which the following description, in connection with the accompanying drawings, is a specification, like letters on the drawings representing like parts.

10 My present invention relates to puzzles, and its object is to provide an interesting toy which will be easy to manufacture, compact and simple in construction, capable of being folded up and carried in the pocket, 15 and of attractive, neat, and ornamental form, and yet which will present an apparently impossible puzzle to solve. To this end I have devised a puzzle of wire, comprising a plurality of wire links and a wire 20 ring which is fitted on one end of the chain of links and surrounded by links of greater diameter than the ring itself, so that at first sight it would appear to be impossible to remove the ring.

25 Referring to the drawings, Figure 1 illustrates the puzzle in extended position, showing the ring at one end of the chain or wire links, these wire links being preferably of somewhat complex form; and Fig. 2 illustrates the manner in which the links may be 30 folded together and the wire ring worked around the same to be removed and the puzzle solved.

As shown in the drawings, my puzzle 35 comprises a neat, compact puzzle of wire links, these links comprising a large end link 1, having the two end portions formed into loops 2 and 3 respectively about a second link 4, with its ends 5 and 6 similarly 40 looped about a third loop 7. This link is preferably of S shape and is adjacent a second S shaped loop 8, each having its respective adjacent end portions looped at 9 and 10, as clearly shown in Fig. 1. A fifth link 45 11, similar in form and size to the second link 4 has its ends looped at 12 and 13 about the link 8. A ring 14 of less diameter than the width of the links 1, 4, or 11, substantially in the proportion shown, is fitted on

the link 1. The puzzle presents the problem 50 of removing the ring 14 from its position shown in Fig. 1, without bending or distorting any of the several links in the entire device. To work the puzzle, the several links must be so folded as to permit the ring 55 14 being slipped thereover and entirely removed from the chain.

Fig. 2 illustrates the manner in which the puzzle is worked, and the ring 14 passed around along and over one arm of each of 60 the several links excepting link 1, simultaneously and out over the other link, the various dotted line positions being clearly delineated. The links 4 and 11 are each first slid upon their respective adjacent links 65 7 and 8, by permitting the loops 5 and 6 of the link 4, and 12 and 13 of the link 11, to slide into the S loop of each link 7 and 8 at the points indicated at 15 and 16 respectively, the links 4 and 7 on one side and links 70 8 and 11 on the other are bent downwardly on the loops 9 and 10 into the position illustrated in Fig. 2. The link 1 is then slid around one arm of the link 4 with the ring 75 14 held thereon until said ring may pass over the several arms of all the other combined links at the point 17, Fig. 2, thence being moved onwardly as shown in dotted portions until entirely taken off.

It will thus be seen that I have provided 80 a neat, compact, interesting puzzle, formed of a plurality of wire links in a manner economical to manufacture, easy to assemble, and presenting a highly interesting and difficult problem.

Having described my invention, what I 85 claim as new and desire to secure by Letters Patent, is:

In a puzzle having five U-shaped wire links with a ring on one extreme end link, 90 said ring being of somewhat smaller diameter than the link on which it is held, each link having the ends of its U-shaped arms pivotally united with the adjacent link and adapted to slide on the said link, excepting 95 the two intermediate links, which said two links are of U form with their ends extended in S shape and with said adjacent ends piv-

totally united to each other permitting a pivotal action thereon only, whereby four of said links may be folded together and the ring removed by manipulating the same around the arms of both **S** shaped ends and the respective adjacent **U**-shaped links simultaneously.

In testimony whereof, I have signed my name to this specification, in the presence of two subscribing witnesses.

DAVID E. FOLLEY.
